UNITED STATES PATENT OFFICE

2,585,678

WINDOW

John H. Preston, Brooklyn, N. Y.

Application August 8, 1947, Serial No. 767,501

2 Claims. (Cl. 20—52)

1

This invention relates generally to windows, and more particularly to a window construction including a pair of similar vertically slideable sashes within channelled frame members and a horizontally swinging sash mounted within each of the slideable sashes, together with novel means for frictionally engaging the vertically sliding sashes and frame, and other novel means for mounting the swinging sashes within the slideable sashes so that said swinging sashes may be completely rotated to facilitate cleaning thereof.

A primary object of this invention is to provide a window construction in which the individual sashes may be easily rotated to facilitate the washing thereof, and to provide a rotatable swinging sash structure which presents uniform appearance on each side thereof, thus avoiding the necessity of reversing the swinging sashes after the washing thereof.

Another salient object of this invention is to provide frictional means on the vertically sliding sash members, which means will avoid the necessity of provision of pulleys and cables and counterweights.

Still another object of this invention, ancillary to the first object mentioned above, is to provide structure whereby windows may be completely and properly cleaned from the interior of the building, wherein such windows are mounted, thus greatly lessening the danger ordinarily associated with the cleaning of windows which cannot be reversed.

Another object of this invention is to provide frictional means, mentioned above, which can be adjusted, the frictional action being achieved by the inter-action of two separate springs and a roller member carried thereby.

And a last object to be specifically mentioned is to provide a device of this character which is relatively inexpensive and practicable to manufacture, extremely simple and convenient to install and to use, and which will give generally efficient and durable service.

With these objects definitely in view this invention resides in certain novel features of construction, combination and arrangement of parts and portions, as will be hereinafter described in detail in the specification, particularly pointed out in the appended claims, and illustrated in the accompanying drawings which form a material part of this application, and in which:

Figure 1 is a perspective view of a window with this invention incorporated therewith;

Figure 2 is an enlarged detailed fragmentary view of an upper lateral portion of a vertically

2

sliding sash, with the friction grip unit assembly recessed therein;

Figure 3 is a vertical transverse sectional view taken on the line 3—3 in Figure 2, certain portions of the figure being shown in elevation to facilitate the illustration;

Figure 4 is a horizontal sectional view, taken on the line 4—4 in Figure 2;

Figure 5 is a horizontal sectional view, taken on the line 5—5 in Figure 6, and showing the horizontally swinging sash member of the inside vertically sliding sash being disposed in four positions;

Figure 6 is a vertical sectional view of the inner and outer vertically sliding sashes when the same are disposed opposite to each other, and showing how the horizontally swinging sash members are each provided with pivot means at one side of each sash and at the top and bottom thereof;

Figure 7 is an enlarged detailed fragmentary view of a portion of the horizontal rail of a swinging sash member, in elevation, and a vertical transverse sectional view of the contiguous portion of the horizontal rail of the vertically sliding sash; and

Figure 8 is a perspective view of a portion of the lower horizontal rail in a vertically sliding sash.

Similar characters of reference designate similar or identical parts and portions throughout the several views of the drawings and throughout the specification.

Referring now to the drawings in detail, it will be noted that this invention includes a window frame having a sill 10, vertical side members 12, and a top cross member 14. The vertical side members 12 are provided with a waling strip 16 and parting strips 18 and 20, thus creating channels to guide the vertical rails 22 of the vertically sliding sashes.

The horizontal rails 24 of the vertically sliding sashes are each recessed as at 26, to receive the head portions 28 of pivot bracket members 30 which are secured to the top and lower ends of one of the vertical rails in each swinging inner sash 23. A pair of rigid straps 32, coextensive in length with the horizontal rails 24, are secured as illustrated best in Figures 7 and 8, to these horizontal rails 24, so as to extend inwardly over the outer edges of the slotted portions 26, these straps being adapted to engage the head 28 of each of the pivot bracket members 30 and to retain the swinging sash members in sliding engagement with the vertically sliding sash members, when the former are being reversed or rotated, as indicated by the dash line representa-

tion.

tion in Figure 5. The rigid straps 32 will ordinarily be secured by simple wood screws 34.

This invention includes a frictional holding means, generally denoted by the numeral 36, recessed into the outer surface of one of the vertical rails 22 in each sliding sash. Each assembly or means 36 includes a friction retaining shoe in the form of a spring 38 of undulating form, apertured at one end for securement by means of a screw 40 and lateral prong means 42, and centrally slotted as at 44 to receive a peripheral portion of a tension regulating roller 46. This roller 46 is provided with axial pintles 48 which ride against the cam forming bends or undulations of said spring 38 on each side of the slot 44, and this roller is engaged and actuated by a flat spring 50 which is apertured at one end and may be held in place on the vertical rail 22, by means of the same screw 40 as is used to hold the undulated spring 38 in place. It will be understood that the recesses 52 for the assembly 36 is of sufficient width and length to allow free play and movements of the springs 38 and 50 and that the roller 46 will also frictionally engage the relatively rigid strap 54 secured to the window frame 12. If preferred, the strap 54 may be recessed into the frame 12, as indicated in Figure 5.

It will be clear that the upper and lower outwardly convexed bends (see Fig. 2) are held, by the inherent resiliency of said spring 38, in friction binding contact with the roller tracking strip 54, while the central or intervening inwardly convexed bend is spaced from said strip 54. Also, the crest of the latter bend is in close proximity to the flat spring 50. The spring 50 urges the roller 46 through said slot 40 and the roller is therefore at all times in frictional but free travelling contact with said strip 54. Spring 50 also keeps the pintles 48 in rollable but friction tracking contact with the stated cam-forming undulations or bends. If, by the operation of the sash, the roller 46 is caused to travel upwardly between the two springs 38 and 50, it will still remain in rolling contact with strip 54. However, the pintles will ride up on the crest of the intermediate bend or cam, thus exerting greater pressure on spring 38. This greater force is also aided by the roller trying to wedge itself into the restricted space between the crest of said bend and intermediate portion of said spring 50. In fact, said bend will tend to flatten out to prevent said roller from losing friction contact with said strip 54. It follows that when the sash goes up the roller 46 goes down and when the sash slides down the roller travels up. Therefore, assuming that one raises the sash to open the same and, looking at Fig. 2, the roller 46 will ride down a slight degree without exerting any appreciable added tension on the spring 38. When the sash is released and allowed to sink under its own weight the roller rides up, locates itself between the center bend of the spring 38 and, in conjunction with its actuating spring 50 it checks the descent and the sash is held in a set position.

The horizontal and vertical rails of the vertical sliding sashes are each provided with inwardly disposed beads or flanges 56 to act as stops or abutments limiting the outward movement of the swinging sashes 23 within the sliding sash members.

Each of the swinging sash members 23 is provided with a pane of glass 58, and the inner edges of each of the rails of the swinging sash members are shaped, as shown at 60, to corre-

spond with the formation of the retaining putty and brad construction 70 used to retain the glass in place. Since both sides of the swinging frame members have a very similar appearance, the swinging sash members need not be reversed, after the same have been washed.

Suitable latching means, generally indicated at 72, and of any suitable character, will be secured to the vertical rails 22 of the sliding sash members, to lock the swinging sash members 23 in position, it being noted that these lock members are provided on each side of the vertically sliding sash members.

The operation of this invention will be clearly understood from the foregoing description of the mechanical details thereof, taken in connection with the above recitation of the objects sought to be achieved by this invention. In recapitulation, it may be added that the frictional engagement units 36 are adjustable, since the rollers 46 may be moved into one or other of the undulations of the spring 38, the amount of frictional action being thereby adjusted. From the above, it will be obvious that a device has been provided allowing the cleaning of windows without actual removal of the sashes, and from inside the building whereon the windows are situated, and that a minimum of equipment is required by this invention to carry out the functions of the device.

Although there has been shown a particular embodiment of this invention, this invention is not limited to this particular embodiment but it is desired to include in the scope of this invention the construction, combination and arrangement of elements cited in the appended claims.

Having described the invention, what is claimed as new is:

1. A sliding sash embodying a frame having a rail provided with a recess, a substantially flat spring located in said recess, a second companion spring also located in said recess and having one end superimposed upon a corresponding end of said first named spring, common fastening means securing said springs together and anchoring same on said rail, the opposite ends of said springs being freely flexible and spaced apart, said second named spring being longitudinally undulated and having a central elongated roller accommodating slot, said second spring constituting a friction retaining member which is adapted to frictionally bind against a relatively fixed window frame member and said undulations functioning as tension varying cams, and a variable tension-regulating roller interposed between the free end portions of said springs, said roller being situated in part in said slot and traversing the tortuous path formed by said undulations between both springs, and said roller having oppositely disposed axial pintles in rollable pressure exerting contact with said cams and serving to vary the pressure of said second named spring against said window frame member, the free end of said first named spring having constant contact with the periphery of said roller and serving to press the latter, by way of said slot, into constant rolling contact with said frame member and also serving to maintain said pintles in constant rolling but variable tensioning contact with said cams.

2. A sliding sash embodying a frame having a rail provided with a recess, a substantially flat spring located in said recess, a second companion spring also located in said recess and having one end superimposed upon a corresponding end of said first named spring, common fastening

means securing said springs together and simultaneously anchoring the same on said rail, the opposite ends of said springs being freely flexible and spaced apart, said second named spring having a central elongated roller accommodating slot, and a pressure exerting and tension varying roller interposed between the free end portions of said springs, said roller being situated in part in said slot and having oppositely disposed outstanding axially arranged pintles in rollable pressure exerting contact with longitudinal portions of the second named spring on opposite sides of said slot, the free end of said first named spring having constant contact with the periphery of said roller and serving to press the latter, by way of said slot, into constant rolling contact with a frame member with which said roller is adapted to cooperate and also serving to maintain said pintles in constant rolling automatic tension varying contact with the longitudinal side portions of said second named spring, the stated one end of said second spring having prong means embedded in said rail and overlying the corresponding end of said first named spring, whereby to assist in maintaining both springs in coacting alignment.

JOHN H. PRESTON.
